UNITED STATES PATENT OFFICE.

HEINRICH KOPPERS, OF ESSEN-ON-THE-RUHR, GERMANY, ASSIGNOR TO H. KOPPERS COMPANY, OF CHICAGO, ILLINOIS, A CORPORATION.

CLOSURE FOR RETORT COKE-OVENs.

1,099,256.

Specification of Letters Patent.

Patented June 9, 1914.

Application filed July 8, 1913. Serial No. 777,831.

To all whom it may concern:

Be it known that I, HEINRICH KOPPERS, a subject of the German Emperor, residing at Essen-on-the-Ruhr, in Germany, have invented certain new and useful Improvements in Closures for Retort Coke-Ovens, of which the following is a specification.

The object of this invention is to effect certain improvements in the construction of packed doors for coke ovens and other retort ovens. It is usual to arrange these doors to make a joint with an iron frame, which is closed all the way around and is connected with the door frame of the adjoining oven, so that the several frames form a continuous protection for the oven walls. A continuous protecting structure of this description can obviously in practice only be conveniently fitted when building a new bank of ovens. It is also very expensive, and the warping of one of the frames involves the adjacent frames more or less. In my invention I avoid the use of this continuous series of frames and make a direct joint between the door and the oven faces, the latter being armored with cast-iron corner bars, to permit of obtaining a good joint with the small bearing surfaces available. The said corner bars extend the whole height of the oven and are fixed in a suitable manner. These bars are stepped so that the door fits against a shoulder, the outward flange of the bar forming with the door a recess into which packing material is introduced. These door structures being independent of one another, they may be applied to any existing oven, and they are inexpensive and independent of the adjacent oven heads. Moreover, defective corner bars can be easily renewed at a low cost.

The invention is illustrated in the accompanying drawing, in which—

Figure 1 is an elevation showing portions of two doors with their framing; Fig. 2 being a horizontal section thereof.

Referring to the drawing, the flue 11 is closed in front by head or facing blocks 12. The girders 13 for anchoring the oven also serve to support the oven head, which is formed by the stones 12. Cast-iron corner bars 14, angular in cross section, are cemented into recesses in the stone blocks, and the two bars at opposite sides of the blocks are held together by bolts 15, distance pieces 16 being provided to keep the bars 14 the

correct distance apart. The door comprises a cast-iron frame 17, into which a panel or body 18 of fire proof material is fitted, and the door is armored in front with a metal plate 19.

The door frame 17 fits with its shoulder 20 against one of the flanges of the adjacent angle bar 14, so that a metal to metal contact is obtained. Between the other flange of the angle bar and the outward extension of the door frame there is a space, which is filled with suitable packing material 21, which may consist of clay, as the packing is not subjected to any pressure.

It will be apparent that in the case of rigid frames, warping renders the insertion of packed doors extremely difficult, as the frame with inserted packing, to take the pressure and make the joint, must be very narrow, and exact in size.

With my improved structure the pressure is taken by the side bars and any warping which may occur can distribute itself along the width of the shoulder on both bars, whereby the above mentioned difficulties are obviated as regards a large number of small distortions.

I claim:

1. Closure for retort coke ovens comprising a pair of metallic reinforcing corner bars secured to the vertical forward edges of the coking chamber-mouth and provided with outwardly extending flanges, a door, and a metallic frame secured to said door and provided with shoulders adapted to engage the corner bars and with flanges extending outwardly from said shoulders, the opposed corner bar-flanges and frame-flanges forming pockets for the reception of a packing material.

2. Closure for retort coke ovens comprising a plurality of spaced parallel coking chambers, a facing block between each pair of adjacent coking chambers, metallic angular corner bars secured to the upright forward edges of each block, and doors having shouldered metallic frames that are adapted to engage the corner bars of adjacent facing blocks.

3. Closure for retort coke ovens comprising a plurality of spaced parallel coking chambers, a facing block between each pair of adjacent coking chambers, metallic angular corner bars extending along the upright forward edges of each block, means

for connecting the corner bars of each block with each other and with the block, and doors having shouldered metallic frames that are adapted to engage the corner bars of adjoining facing blocks.

4. Closure for retort coke ovens comprising a plurality of spaced parallel coking chambers, a facing block between each pair of adjacent coking chambers, metallic angular corner bars secured to the upright forward edges of each block, and doors having shouldered metallic frames that are

adapted to engage the corner bars of adjacent facing blocks, said frames having flanges that extend forwardly from their shoulders to form in conjunction with the corner bars, packing receiving channels. 15

In testimony whereof I have signed my name to this specification in the presence of two subscribing witnesses.

HEINRICH KOPPERS.
